(57) **CLAIM**

The ornamental design for the “drawer for holding different types of beverage cartridges,” as shown and described.

DESCRIPTION

FIG. 1 is a perspective view of the drawer for holding different types of beverage cartridges;

FIG. 2 is a perspective view thereof showing the drawer extended outward;

FIG. 3 is a perspective view thereof showing the drawer extended outward and with a beverage cartridge shown in phantom;

FIG. 4 is a front view thereof;

FIG. 5 is a right side view thereof;

FIG. 6 is a rear view thereof;

FIG. 7 is a left side view thereof;

FIG. 8 is a top view thereof; and,

FIG. 9 is a bottom side view thereof.

The broken lines in FIG. 3 are for the purpose of illustrating the environment and form no part of the claimed design.

1 Claim, 5 Drawing Sheets
